UNITED STATES PATENT OFFICE

2,538,415

ELECTRIC MOTOR CONTROL SYSTEM

William K. Ergen, Minneapolis, Minn., assignor
to Minneapolis-Honeywell Regulator Company,
Minneapolis, Minn., a corporation of Delaware

Application April 19, 1945, Serial No. 589,224

16 Claims. (Cl. 318—28)

1

This invention relates to the field of electrical control devices, and more particularly to electrical telemetric systems in which the transmitter and receiver comprise endless resistance members similarly tapped and cooperating with contacting sliders.

It is an object of my invention to provide an improved telemetric system in which the contact friction in the transmitting member is reduced by reducing the number of sliding contacts.

It is another object of my invention to provide a telemetric system having improved sensitivity due to a novel interconnection of taps and a novel arrangement of sliders.

It is a further object of my invention to provide a telemetric system in which the transmitter and receiver are tapped endless resistance members, the former having a single slider and the latter comprising three sliders unitarily mounted, the angles between the sliders being not less than the angles between the taps on the members.

Various other objects, advantages, and features of novelty which characterize my invention are pointed out with particularity in the claims annexed hereto and forming a part hereof. However, for a better understanding of the invention, its advantages, and objects attained by its use, reference should be had to the subjoined drawing which forms a further part hereof, and to the accompanying descriptive matter, in which I have illustrated and described certain preferred embodiments of my invention. In the drawing,

Figure 1 is a schematic representation of a simplified embodiment of my invention, and

Figure 2 is a schematic showing of a more generalized embodiment of my invention.

Construction of Figure 1

Referring first to Figure 1, I have shown a telemetric system comprising a transmitter 10 and a receiver 11. The transmitter is mechanically actuated by a condition responsive mechanism 12. The system is shown as energized from a source 13 of alternating current through a transformer 14, and the system supplies a signal to an amplifier 15 which is supplied with power from source 13. The amplifier energizes a motor 16, jointly with source 13, and operation of the motor is effective upon the receiver to reduce to zero the signal fed to the amplifier and also operate the controlling mechanism 17.

Transmitter 10 is shown to comprise an endless uniform resistance winding 20 which is tapped at three equidistant points 21, 22, and 23. A contacting slider 24 is pivotally mounted

2

for cooperation with winding 20 to make electrical connection therewith at any point around its circumference, and is rotated with respect to the winding in response to a condition by a mechanism 12 which will now be described.

Purely by way of illustration I have shown my invention as embodied in a liquid level control system. Liquid is supplied to a tank 25 through a conduit 26 having a valve 27 arranged for motor operation. A float 30 is mounted by any suitable means (not shown) for vertical movement in the tank as the level of the liquid changes, and a cord 31 fastened to the float is arranged to pass around a drum 32 mounted for unitary rotation with slider 24, from which it is suitably electrically insulated. Thus, as the level of liquid in the tank 25 falls, slider 24 is caused to rotate in a clockwise direction with respect to winding 20: when the level of the liquid rises, slider 24 is moved in a counter-clockwise direction by any suitable spring or other conventional means (not shown). It will be appreciated that any equivalent mechanism such as a rack and pinion drive may be substituted for the arrangement disclosed if desired.

Receiver 11 is shown to comprise an endless uniform resistance winding 33 tapped at three equidistant points 34, 35, and 36. As will later be pointed out, there is no necessity that only three taps be provided on each winding: any desired number of taps greater than three may also be used. Moreover, although I have illustrated windings 20 and 33 as being circular in outline and described them as being uniform, and although the taps are recited as mutually equidistant, these features also are matters of choice only, since they are required only in an embodiment of the invention in which the angular displacement of the transmitter and the receiver from respective zero datum points are desired to be always equal.

A member 37 of insulating material is mounted in pivotal relationship with winding 33 and carries a plurality of mutually insulated contacting sliders 40, 41, and 42 arranged to make electrical contact with the winding at any point on its circumference. Member 37 is arranged for rotation with respect to winding 33 by operation of motor 16 as will presently be set forth in greater detail. In this form of my invention, sliders 40, 41, and 42 are mutually equidistant, but it must be understood that, so long as the angle between sliders 40 and 41 and that between sliders 40 and 42 are not less than the greatest angular displacement between any two

adjacent taps on winding 33, it is not necessary that the angles between the sliders be equal or equal to the angles between the taps.

Taps 21, 22, and 23 of transmitter 10 are connected respectively with taps 34, 35, and 36 of receiver 11 by conductors 39, 44, and 45. This also is a matter of preference, as it is only necessary that the progression of taps around the windings be sequential: the sequence may progress around the two windings in the same or in opposite directions at the choice of the designer.

The telemetric system made up of transmitter 10 and receiver 11 is energized from a source 13 of alternating voltage of a desired frequency through transformer 14 which has a primary winding 46 and a secondary winding 47. Primary winding 46 is connected to source 13 through conductors 50, 51, and 52 and conductors 53, 54, and 55. The system is energized from secondary winding through a transmitter ground connection 56 connected to one end of secondary winding 47, a receiver ground connection 57, resistor 49, conductor 48, slider 40, a portion of winding 33, one or more of conductors 39, 44, and 45, depending upon the position of member 24, a portion of winding 20, slider 24, and conductor 58.

Amplifier 15 may be of any desired type in which the voltage of the output is substantially either in phase with or 180 degrees out of phase with the input voltage: amplifiers introducing such low phase shift are known, and details of the structure of amplifier 15 are therefore not included in this application. The amplifier includes its own power supply, energized through terminals 59 and 60, and also has signal input terminals 61 and 62 and output terminals 63 and 64. Sliders 41 and 42 of receiver 11 are respectively connected to input terminals 61 and 62 of amplifier 15 by conductors 65 and 66. Power is delivered to the amplifier from source 13 through conductors 50 and 67 and conductors 53 and 68.

Motor 16 is shown to comprise a rotor 70 mounted on a shaft 79, a "line phase" stator winding 71, and an "amplifier phase" stator winding 72. The motor is arranged in driving relation with valve 27 and member 37 through such gear reduction means as may be desirable: this drive means is suggested by shaft 43. While the motor may comprise any suitable number of electrical poles, I have shown it to comprise a pair of such poles, which conventionally comprise four mechanical poles spaced about the stator by 90 mechanical degrees.

As is well known to those skilled in the art, if one electrical pole of such a motor is energized by a first alternating voltage and the second electrical pole is energized by a second alternating voltage in quadrature therewith, the motor will operate, the direction of operation of the motor being determined by which of the voltages leads and which lags.

Associated with motor 16 are a pair of capacitors 73 and 74. Capacitor 73 is connected in a series circuit 75 with winding 71 by conductor 76, and the circuit is continuously energized from source 13 by conductors 50, 51, and 77 and conductors 53, 54, and 80. The capacitance of capacitor 73 is so chosen, with respect to the inductance of winding 71, that at the frequency of source 13 the series circuit is resonant, thus promoting efficient operation of the motor. The voltage drop across winding 71 leads that of the source by approximately 90 degrees, the

exact angle depending on the ohmic resistance of winding 71.

Capacitor 74 is connected in a parallel circuit 81 with winding 72 by conductors 82 and 83, and the parallel circuit is connected to output terminals 63 and 64 of amplifier 15 by conductors 84 and 85. The capacitance of capacitor 74 is so chosen, with respect to the inductance of winding 72, that at the frequency of source 13 the parallel circuit is resonant, again promoting efficient operation of the system. The voltage drop across winding 72 is in phase with the output of the amplifier.

It should be understood that substitution of motors of other types together with known control systems therefor is an obvious expedient to those skilled in the art, when such other types of motors are considered more advantageous.

Operation of Figure 1

In order to understand the operation of my invention, the points of contact of sliders 24, 40, 41, and 42 with the associated resistance windings, at any instant, are identified by reference numerals 86, 87, 90, and 91, respectively. It will be observed that a circuit mesh constituting a Wheatstone bridge may be traced as follows: tap 21, conductor 39, tap 34, that portion of resistance winding 33 including point 81, tap 36, conductor 45, tap 23, and that portion of resistance winding 20 including point 86. Points 86 and 87 can be considered the input terminals of the bridge, which is energized from transformer 14, and conductors 39 and 45 may be considered the output conductors of the bridge.

When sliders 24 and 40 are in such a position that the angle K is equal to the angle M as shown in the figure, the bridge is balanced and there is no potential difference appearing between conductors 39 and 45, that is, between taps 34 and 36. For any other relative position of sliders 24 and 40, a potential difference appears between taps 34 and 36, tending to cause flow of current from tap 34 to tap 36 through tap 35. These currents cause IR drops in the resistance winding, and these in turn are picked off by sliders 41 and 42, so that a voltage is impressed on amplifier 15 whose magnitude and phase depend on the relationship between the positions of slider 24 and slider 40. As a result of this, the amplifier supplies an output voltage to stator winding 63 having the phase characteristics indicated above.

Suppose the level of liquid in tank 25 rises, resulting in counterclockwise movement of slider 24. Angle K becomes greater than angle M. Then in the bridge referred to the voltage between conductors 39 and 45, and hence that between sliders 41 and 42, is substantially 180 degrees out of phase with the voltage between the right and left secondary terminals of transformer 14, and therefore in phase with source 13: this voltage is transmitted without appreciable phase shift through amplifier 15 and impressed upon winding 72 of motor 16. Since winding 71 is continuously energized with a voltage 90 degrees out of phase with that of the source, operation of motor 16 takes place in a first direction.

The connection to winding 72, and such gear reductions as are included in means 43, are so chosen that when thus energized motor 16 operates in a direction to increase angle M, and this operation continues until angle M is made equal

to angle K. When this happens the bridge is balanced, no signal is transmitted through the amplifier, and energization of winding 72 is interrupted. Although winding 71 continues to be energized, this is not sufficient to maintain rotation of rotor 70 of motor 16.

If the level of liquid in tank 25 falls instead of rising, exactly the opposite effect takes place in each step of the operation thus far traced, and these details need not be repeated. If, however, due to interrupted energization of the system or to some other cause, slider 24 passes tap 21 into the portion of winding 20 between taps 21 and 22, while slider 40 is still between taps 34 and 36, a different condition arises. For this special and transitory case, the bridge explanation is not valid, a much more complicated network taking the place of the bridge. However, it is found that movement of slider 40 follows that of slider 24 through this critical portion of its range just as it does when the sliders are in similar portions of their resistance windings.

Since both slider 24 and slider 40 are rotatable through 360 degrees, it sometimes occurs that the former comes to rest exactly on one of the taps on winding 20. Where the output to the amplifier should be zero, slider 40 must come to rest on the corresponding tap of winding 33, and this will result in a direct short circuit across the secondary winding. To prevent this from having an injurious effect on the transformer, the slider may be especially wound, but I prefer to insert resistance 49 in series with the sliders so that a direct short circuit can at no time take place.

The foregoing is a description of a specific embodiment of my invention, and it will be seen that a maximum signal is provided to the amplifier when slider 24 is displaced from the related position of slider 40 by one-third of a circle, with slider 40 at or near tap 36 and with slider 24 at or near tap 21. However, a much greater sensitivity is attained by the practice of my invention if the angle between taps 21 and 22 is reduced: a movement of the responsive slider through a given angle is effective to cause a much greater voltage unbalance of the bridge if the angle between the taps is decreased. For a disclosure and description of this embodiment of my invention, attention is now directed to Figure 2.

Construction and operation of Figure 2

Since the structure of Figure 2 is very similar to that of Figure 1, I have used in Figure 2 reference numerals of a series from 101 to 200 which are the same as reference numerals from 1 to 100 for members of Figure 1 having analogous functions. Thus, Figure 2 shows a telemetric system comprising a transmitter 110 and a receiver 111. The system is shown as energized from a source 113 of alternating current through a transformer 114 and the system supplies a signal to an amplifier 115 supplied with power from source 113. The amplifier energizes a motor 116 jointly with source 113, and operation of the motor is effective upon the receiver to reduce to zero the signal fed to the amplifier, and also operates an indicator 117.

Transmitter 110 is shown to comprise an endless uniform resistance winding 120 having a plurality of equally spaced taps, in this case seven in number, of which two are indicated by the reference numerals 121 and 123. A contacting slider 124 is pivotally mounted for coopera-

tion with winding 120 to make electrical contact therewith at any point around its circumference, and is rotated with respect to the winding in response to a condition. In order to avoid unnecessary complication of the drawing, the means by which slider 124 is actuated in response to the condition is not specifically illustrated in this figure.

A member 137 of insulating material is schematically shown as mounted in pivotal relationship with winding 133 and carries a plurality of mutually electrically insulated contacting sliders 140, 141, and 142, arranged to make electrical contact with the winding at any point on its circumference. Member 137 is arranged for rotation with respect to winding 133 by operation of motor 116 which will presently be set forth. In this embodiment of my invention, sliders 141 and 142 are equally spaced from slider 140, the spacing being the same as that between the taps on winding 133.

Taps 121 and 134 are joined by conductor 139, taps 123 and 136 are joined by conductor 145, and the remaining taps are similarly joined by suitable conductors in the proper sequence.

The system is energized from source 113 through transformer 114, which has a primary winding 146 and a secondary winding 147. The primary winding is energized from source 113 through conductors 152 and 153. The system is energized from secondary winding 147 through transmitter ground connection 156 connected to one end of secondary winding 147, receiver ground connection 157, conductor 148, resistor 149, slider 140, a portion of winding 133, one or more of conductors 139, 145, and so forth, depending on the position of slider 140, a portion of winding 120, and slider 124.

Amplifier 115 is shown to have power input terminals 159 and 160, signal input terminals 161 and 162, and output terminals 163 and 164. Sliders 141 and 142 of receiver 111 are respectively connected to input terminals 161 and 162 of amplifier 115 by conductors 165 and 166. Power is delivered to amplifier 115 from source 113 through conductors 167 and 168. The amplifier has the same structure and function as that described in Figure 1, and details of the structure are omitted here for the same reason that they were omitted from the first figure.

Motor 116 is in all respects identical with motor 16, but is more schematically illustrated. The capacitors explicitly disclosed in Figure 1 are comprised within the motor housing in Figure 2, and the motor is energized from the amplifier through conductors 184 and 185 and from source 113 through conductors 177 and 180.

The detailed mechanical connection between motor 116 and member 137 carrying sliders 140, 141, and 142 is suggested schematically in Figure 2, and shaft 179 of motor 116 is also shown as being extended through suitable means 143 to operate the index of indicator 117 over a scale fixed with respect thereto.

In Figure 2 the bridge relationship between corresponding portions of winding 120 and 133 is more clearly evident than in Figure 1, and the method of operation in this case is exactly the same as that recited in detail in connection with the previous figure. From a comparison of the two figures it is evident that a displacement of five degrees, for example, in slider 124 of Figure 2 is effective to cause the signal to amplifier 115 which is seven-thirds the corresponding signal supplied to amplifier 15 due to a displacement of

slider 24 through the same angle with respect to winding 20.

Numerous objects and advantages of my invention have been set forth in the foregoing description, together with details of the structure and function of the invention, and the novel features thereof are pointed out in the appended claims. The disclosure, however, is illustrative only, and I may make changes in detail, especially in matters of shape, size and arrangement of parts, within the principle of the invention, to the full extent indicated by the broad general meaning of the terms in which the appended claims are expressed.

I claim as my invention:

1. In a device of the class described, in combination: a transmitting device and a receiving device, each device comprising an endless resistance member, at least three taps, and a slider, the taps of each resistance member dividing the member into at least three sections; means connecting corresponding taps of the two devices together, said sliders and the taps at the opposite ends of the section of the receiving resistance member engaged by the slider thereof defining respectively first and second pairs of electrically spaced points; a source of electrical energy adapted for transmission along a single pair of conductors; means energizing one only of said pairs of electrically spaced points from said source; and means responsive to the voltage across the other of said pairs of electrically spaced points.

2. In a device of the class described, in combination: a transmitting device and a receiving device, each device comprising an endless resistance member, at least three taps, and a slider, the taps of each resistance member dividing the member into at least three sections, corresponding sections of the resistance members being of the same angular length; means connecting corresponding taps of the two devices together, said sliders and the taps at the opposite ends of the section of the receiving resistance member engaged by the slider thereof defining respectively first and second pairs of electrically spaced points; a source of electrical energy adapted for transmission along a single pair of conductors; means energizing one only of said pairs of electrically spaced points from said source; and means responsive to the voltage across the other of said pairs of electrically spaced points.

3. In a device of the class described, in combination: a transmitting device and a receiving device, each device comprising a uniform endless resistance member, at least three taps, and a slider, the taps of each resistance member dividing the member into at least three sections, corresponding sections of the resistance members being of the same angular length; means connecting corresponding taps of the two devices together, said sliders and the taps at the opposite ends of the section of the receiving resistance member engaged by the slider thereof defining respectively first and second pairs of electrically spaced points; a source of electrical energy adapted for transmission along a single pair of conductors; means energizing one only of said pairs of electrically spaced points from said source; and means responsive to the voltage across the other of said pairs of electrically spaced points.

4. In a device of the class described, in combination: a transmitting device and a receiving device, each device comprising an endless resistance member, at least three taps, and a slider,

the taps of each resistance member dividing the member into at least three sections; means connecting corresponding taps of the two devices together, said sliders and the taps at the opposite ends of the section of the receiving resistance member engaged by the slider thereof defining respectively first and second pairs of electrically spaced points; a source of electrical energy adapted for transmission along a single pair of conductors; means energizing one only of said pairs of electrically spaced points from said source; and means responsive to the voltage across the other of said pairs of electrically spaced points, said last named means including a pair of further sliders oppositely spaced from said slider of said receiver and contacting said resistance member of said receiver, the angular spacing between said further sliders being no less than the greatest spacing between said taps of said resistance member of said receiver.

5. In a device of the class described, in combination: a transmitting device and a receiving device, each device comprising an endless resistance member, at least three taps, and a slider, the taps of each resistance member dividing the member into at least three equal sections; means connecting corresponding taps of the two devices together, said sliders and the taps at the opposite ends of the section of the receiving resistance member engaged by the slider thereof defining respectively first and second pairs of electrically spaced points; means for impressing a potential across one of said pairs of electrically spaced points only; and means responsive to the voltage across the other of said pairs of electrically spaced points, said last named means including a pair of further sliders equally and oppositely spaced from said slider of said receiver and contacting said resistance member of said receiver, the angular spacing between said further sliders being equal to the spacing between said taps of said resistance members.

6. In a device of the class described, in combination: a transmitting device and a receiving device, each device comprising an endless resistance member, at least three taps, and a slider, the taps of each resistance member dividing the member into at least three sections; means connecting corresponding taps of the two devices together, said sliders and the taps at the opposite ends of the section of the receiving resistance member engaged by the slider thereof defining respectively first and second pairs of electrically spaced points; a source of electrical energy adapted for transmission along a single pair of conductors; means energizing one only of said pairs of electrically spaced points from said source; means responsive to the voltage across the other of said pairs of electrically spaced points; means actuating said slider of said transmitting device in response to a condition; and motor means actuated by said voltage responsive means.

7. In a device of the class described, in combination: a transmitting device and a receiving device, each device comprising an endless resistance member, at least three taps, and a slider, the taps of each resistance member dividing the member into at least three sections; means connecting corresponding taps of the two devices together; said sliders and the taps at the opposite ends of the section of the receiving resistance member engaged by the slider thereof defining respectively first and second pairs of electrically spaced points; a source of electrical energy

adapted for transmission along a single pair of conductors; means energizing one only of said pairs of electrically spaced points from said source; means responsive to the voltage across the other of said pairs of electrically spaced points, said means including a pair of further sliders oppositely spaced from said slider of said receiver and contacting said resistance member of said receiver, the angular spacing of said sliders being no less than the greatest spacing between said taps of said resistance member of said receiver; means actuating said slider of said transmitting device in response to a condition; and motor means actuated by said voltage responsive means.

8. In a device of the class described, in combination: a transmitting device and a receiving device, each device comprising an endless resistance member, at least three taps, and a slider, the taps of each resistance member dividing the member into at least three equal sections; means connecting corresponding taps of the two devices together; said sliders and the taps at the opposite ends of the section of the receiving potentiometer engaged by the slider thereof constituting two pairs of electrically spaced points; means for impressing a potential across one of said pairs of electrically spaced points only; means responsive to the voltage across the other of said pairs of electrically spaced points, said means including a pair of further sliders equally and oppositely spaced from said slider of said receiver and contacting said resistance winding of said receiver, the angular spacing of said sliders being equal to the spacing between said taps of said resistance member of said receiver; means actuating said slider of said transmitting device in response to a condition; and motor means actuated by said voltage responsive means.

9. In a device of the class described, in combination: a transmitting device and a receiving device, each device comprising an endless resistance member, at least three taps, and a slider, the taps of each resistance member dividing the member into at least three sections; means connecting corresponding taps of the two devices together; said sliders and the taps at the opposite ends of the section of the receiving resistance member engaged by the slider thereof defining respectively first and second pairs of electrically spaced points; means for impressing a potential across one of said pairs of electrically spaced points only; means responsive to the voltage across the other of said pairs of electrically spaced points; means actuating said slider of said transmitting device in response to a condition; motor means actuated by said voltage responsive means; and means connecting said sliders of said receiving device with said motor means for unitary actuation thereby.

10. In a device of the class described, in combination: a transmitting device and a receiving device, each device comprising an endless resistance member, at least three taps, and a slider, the taps of each resistance member dividing the member into at least three sections; means connecting corresponding taps of the two devices together; said sliders and the taps at the opposite ends of the section of the receiving resistance member engaged by the slider thereof defining respectively first and second pairs of electrically spaced points; means for impressing a potential across one of said pairs of electrically spaced points only; means responsive to the voltage across the other of said pairs of electrically spaced points, said last named means including a pair of

further sliders oppositely spaced from said slider of said receiver and contacting said resistance member of said receiver, the angular spacing of said sliders being no less than the least spacing between said taps of said resistance member of said receiver; means actuating said slider of said transmitting device in response to a condition; motor means actuated by said voltage responsive means; and means connecting said sliders of said receiving device with said motor means for unitary actuation thereby.

11. In a device of the class described, in combination, a transmitting device and a receiving device, each device comprising a uniform endless resistance member, at least three taps, and a slider, the taps of each resistance member dividing the member into at least three equal sections; means connecting corresponding taps of the two devices together; said sliders and the taps at the opposite ends of the section of the receiving resistance member engaged by the slider thereof defining respectively first and second pairs of electrically spaced points; means for impressing a potential across one of said pairs of electrically spaced points only, and means responsive to the voltage across the other of said pairs of electrically spaced points; said last named means including a pair of further sliders equally and oppositely spaced from said slider of said receiver and contacting said resistance winding of said receiver, the angular spacing of said sliders being equal to the spacing between said taps of said resistance member of said receiver; means actuating said slider of said transmitting device in response to a condition; and motor means actuated by said voltage responsive means; and means connecting said sliders of said receiving device with said motor means for unitary actuation thereby.

12. In a device of the class described in combination: first and second endless impedance members, said members being provided with like numbers of equally spaced taps; a movable slider engaging one of said members for continuously making electrical connection therewith; a first movable slider similarly engaging the second of said members and further sliders similarly engaging said second member and oppositely spaced from said first slider, the spacing between said first slider and said further sliders being the same as the spacing between said taps; electrically conducting means joining each tap on one of said members with a tap on the other member in the same sequence; means maintaining an alternating potential difference between said slider of said first member and said first slider of said second member; and electrically responsive means connected between said further sliders of said second member.

13. In a device of the class described in combination: first and second endless resistance members, said members being provided with like numbers of equally spaced taps; a movable slider engaging one of said members for continuously making electrical connection therewith; a first movable slider similarly engaging the second of said members and further sliders similarly engaging said second member and oppositely spaced from and movable unitarily with said first slider, the spacing between said first slider and said further sliders being the same as the spacing between said taps; electrically conducting means joining each tap on one of said members with a tap on the other member in the same sequence; means maintaining an alternating potential dif-

ference between said slider of said first member and said first slider of said second member; means actuating said slider of said first member in response to a condition; voltage responsive means for actuating said sliders on said second member, and means connecting said last named means between said further sliders of said second member.

14. In a device of the class described in combination: first and second endless impedance members, said members being provided with like numbers of taps; a movable slider engaging one of said members for continuously making electrical connection therewith; a first movable slider similarly engaging the second of said members and further sliders similarly engaging said second member and oppositely spaced from and movable unitarily with said first slider, the spacing between said first slider and said further sliders being no less than the greatest spacing between said taps; electrically conducting means joining each tap on one of said members with a tap on the other member in the same sequence; means maintaining an alternating potential difference between said slider of said first member and said first slider of said second member; and electrically responsive means connected between said further sliders of said second member.

15. In a device of the class described, in combination: a transmitting device and a receiving device, each device comprising an endless resistance member, at least three taps, and movable means for making electrical connection to said resistance member at any point therealong, the taps of each resistance member dividing the member into at least three sections; means connecting corresponding taps of the two devices together; said movable means of said receiving device comprising a pair of angularly spaced sliders contacting said resistance member of said device, the angular spacing between said sliders being no less than the greatest spacing between said taps of said receiver; said pair of sliders defining a first pair of electrically spaced points, and said movable means of said transmitting device and a point at a potential midway between the potentials of said pair of sliders constituting a second pair of electrically spaced points; a source of electrical energy adapted for transmis-

sion along a single pair of conductors; means energizing one only of said pairs of electrically spaced points from said source; and means responsive to the voltage across the other of said pairs of electrically spaced points.

16. In a device of the class described, in combination: a transmitting device and a receiving device, each device comprising an endless resistance member, at least three taps, and a slider, the taps of each resistance member dividing the member into at least three sections; means connecting corresponding taps of the two devices together; a pair of further sliders oppositely spaced from said slider of said receiving device and contacting said resistance member of said device, the angular spacing between said further sliders being no less than the greatest spacing between said taps of said receiver; said pair of further sliders defining a first pair of electrically spaced points, and said slider of said transmitting device and a point at a potential mid-way between the potentials of said further sliders constituting a second pair of electrically spaced points; a source of electrical energy adapted for transmission along a single pair of conductors; means energizing one only of said pairs of electrically spaced points from said source; and means responsive to the voltage across the other of said pairs of electrically spaced points.
